UNITED STATES PATENT OFFICE.

JOSEPH L. DE STEIGER, OF LA SALLE, ILLINOIS.

NECKTIE-RETAINER.

1,263,214.

Specification of Letters Patent. Patented Apr. 16, 1918.

Application filed August 27, 1917. Serial No. 183,385.

To all whom it may concern:

Be it known that I, JOSEPH L. DE STEIGER, a citizen of the United States, residing at La Salle, in the county of La Salle and State 5 of Illinois, have invented new and useful Improvements in Necktie-Retainers, of which the following is a specification.

My present invention pertains to bow-ties of the made-up variety; and consists in a 10 peculiar and advantageous retainer for bow neckties, as hereinafter described and definitely claimed.

In the accompanying drawings, which are hereby made a part hereof:

15 Figure 1 is a top plan view of a necktie equipped with my novel retainer.

Fig. 2 is a rear elevation of the same.

Fig. 3 is a perspective of the retainer *per se*.

20 Fig. 4 is an enlarged transverse section, taken in the plane indicated by the line 4—4 of Fig. 3.

Similar numerals of reference designate corresponding parts in all of the views of 25 the drawings.

The tie body or bow-necktie proper is preferably of the ordinary well-known form as shown and indicated by 1, and it may be made of any material suitable to its purpose 30 without affecting my invention.

Suitably secured in the tie-body 1 is the comparatively stiff or rigid bar 2 of my novel retainer. The said bar 2 is curved in the direction of its length—*i. e.*, is of bow 35 form in edge elevation, and is provided at its middle with a seat 3, formed by bending or pressing it to about the extent indicated.

In addition to the bar 2 which is the main bar of the retainer, the improved retainer 40 comprises a curvilinear spring or resilient strip 4, flared at its ends, as indicated by 5, and a metallic binding loop 6 which has for its function to strongly connect the bar 2 and the strip 4 in opposed relation at the 45 middles thereof. The said binding loop 6 is tightly arranged in the seat of the bar 2, and hence there is no liability of the loop casually moving or changing its position in the direction of the length of the bar and strip.

50 Said loop, however, serves to strongly connect the bar 2 and strip 4 together in such manner that there is no liability of the retainer breaking in practice, no matter how roughly it is manipulated, and no likelihood 55 of the bar 2 and strip 4 becoming casually

disconnected. As clearly shown the strip 4 is slightly narrower than the bar 2, in the preferred embodiment of the invention, and the end portions of the strip in combination with the opposed portions of the bar 2 form 60 flaring mouths adapted to readily receive the end portions of the flaps of a turn-down collar. Moreover, it will be appreciated that by virtue of the joining loop arranged in the seat 3 of the bar 2 and embracing the 65 said bar 2 and the strip 4, the retainer may be very expeditiously and cheaply manufactured without the employment of expensive machinery.

It will be manifest from the foregoing 70 that my novel retainer as a unit rests back of the bow necktie to which it is connected. Consequently in using the retainer to effect connection of the tie to a collar of the type defined, it is simply necessary for the operator to so manipulate the tie and retainer 75 that the ends of the front flaps of the collar are received and clamped between the end portions of the strip 4 and the bar 2, whereby the tie will be fixed to and held in proper 80 relative arrangement on the collar, without liability of casual loosening or displacement. When, however, it is desired to remove the tie, the same may be readily accomplished by slight manipulation of the retainer relative 85 to the collar.

Having described my invention, what I claim and desire to secure by Letters Patent, is:

1. As a new article of manufacture, a retainer for neckties, comprising a main bar having a seat at its middle, a spring strip opposed to the back of the main bar, and a connecting loop tightly surrounding the main bar and the spring strip and arranged 90 in the seat of the former.

2. As a new article of manufacture, a necktie retainer, comprising a curvilinear main bar having a seat at its middle, a spring strip opposed to the back of the seat 100 in the main bar and having end portions adapted to engage a collar, and means connecting the strip and the bar.

In testimony whereof I have hereunto set my hand in presence of two subscribing witnesses.

JOSEPH L. DE STEIGER.
